PLUNGER LIFT CONTROL

Harold W. Fletcher and Ralph Neuhaus, Houston,
Tex., assignors to Hughes Tool Company, Houston,
Tex., a corporation of Texas

Application February 18, 1935, Serial No. 7,107

11 Claims. (Cl. 103—52)

Our invention relates to method of and apparatus for controlling the operation of a plunger lift device.

It is an object of the invention to control the release of the gaseous fluid pressure from the well after the load of liquid is discharged, and to also control the point of entrance of the pressure fluid to the eduction tube in the well.

We aim to provide an installation that is saving in the amount of gaseous pressure fluid necessary for operation and which will also accelerate the operation of the device so that more strokes of the plunger per hour are possible.

It is an object to provide a valve, automatically operated by the movement of the plunger, to control the inlet of the pressure fluid below the plunger at a point above the liquid inlet at the lower end of the eduction tube.

The invention also includes the construction of the control valve whereby it functions properly and is adapted to be operated by the plunger.

In the drawing herewith, Fig. 1 is a side view partly in central vertical section of a plunger lift installation embodying the invention.

Fig. 2 is a transverse section on the plane 2—2 of Fig. 3.

Fig. 3 is a vertical sectional detail of the valve on the plane 3—3 of Fig. 2.

Fig. 4 is a sectional detail on the plane 4—4 of Fig. 2.

The plunger lift installation shown includes a well casing 1 which extends into the well for the desired depth to retain the walls of the well bore. It has a casing head 2 of special construction, having two lateral ports; an inlet port 3 for pressure fluid, and an outlet port 4 for liquid being pumped. Below the outlet port is an inwardly extending flange 5 to fit closely about the eduction tube 6 and support the same.

The upper end of the casing head is closed by a cap 7 which has an axial passage threaded to connect with the tube extension 8 at its upper end. On its inner end it has a ground seat to receive the upper end of the perforated nipple 9 upon the eduction tube.

The eduction tube 6 is connected with the nipple 9 by the coupling 10 which fits in a seat upon the flange or partition 5 and forms a seal therewith. The lower end of the tubing is extended downwardly to be submerged the desired amount within the liquid 11 in the well. The lower end of the tube is closed by a cap 12 perforated to admit liquid and gas to the tube.

The plunger is shown at 13 and is of the usual construction with an upwardly closing valve 14,

the stem 15 of which extends below the body of the valve support 16.

Spaced the desired distance above the lower end of the tube 6 is a valve housing 17 which is coupled into the tubing as shown. One wall of the housing is made thick as shown in Fig. 2. This wall has a chamber 18, closed on its outer side by a plate 19 which may be welded in place. From the chamber 18 are two opposite lateral branches 20 providing valve compartments 21 formed by a cylindrical bore extending transversely of said chamber. From these compartments are a plurality of downwardly and inwardly formed passages 22 leading to the interior of the housing. See Fig. 4.

The valve includes a cylindrical head 23 which fits closely, but rotatably, within the bore 20. The ends within the compartments are formed hollow and on the lower side are openings 24 from the hollowed recesses, arranged to be brought into registration with the passages 22 when the valve is opened. The head 23 of the valve has a sleeve 25 thereon which may be secured rotatably thereon by a set screw 26. On the side of the sleeve 25 facing inwardly is a finger 27 projecting into the path of travel of the plunger. Above the valve the sleeve 25 has attachment at 28 to a coiled spring 29 supported in the upper portion of chamber 18. Said spring tends to hold the sleeve in position with the finger extending radially inward. As will be seen in Fig. 3 the set screw 26 fits through a slot 30 in the sleeve 25 and permits only a limited rotative movement of the sleeve on the valve.

At the upper end of the well the discharge pipe 31 has a main branch 32 leading to the upper end of a tank or container 33 so that the fluid from the well will be discharged, on each stroke, into said tank.

The liquid will drain out of said tank through the pipe 34 in which is placed the choke valve 35 to control the rate of drainage. Beyond the choke valve 35 a pipe 36 is connected so as to allow escape of gas from the upper end of the tank with which said pipe 36 is connected.

There is an automatic valve 37 of common construction connected in the gas line 38. The stem of said valve is connected with a diaphragm set in the housing 39. The outer end of said housing is connected by a bypass line 40 with the discharge line 41, so as to receive the well pressure thereon.

The upper end of the eduction pipe extension 42 may be connected with the discharge line 41 through pipe 43 by opening valve 44, which is

normally closed. When the valve 39 is opened the plunger may pass upwardly above valve 40 which may then be closed to catch the plunger when it becomes desirable to do so.

- 5 In operation the plunger 13 with its load of liquid is raised in the eduction tube by the pressure of gas or air in the casing 1 entering below the plunger after depressing the head of liquid 11 in the well. As the plunger contacts with the finger 25 on the valve 22 on the upward stroke of the plunger, it will rotate the valve so as to bring the openings 23 therein into registration with the passages 21 and thus allow the gas in the casing to enter directly into the tube behind 10 the plunger, thereby accelerating the action of the plunger and allowing the liquid to fill into the lower end of the tubing below the valve.
- 15

As the load of liquid is discharged through the outlets 4 and 30 to the container 31 the fluid 20 pressure will also act through bypass 31 upon valve 35 and close it and hold it closed until the fluid pressure is decreased below a predetermined value, whereupon said valve will open. The plunger will pass the outlet and will be stopped by 25 fluid compressed in the dead upper end of the extension 8 and the valve in the plunger will be forced open. The plunger will then start to fall and as the exhaust of the gas in the tube is prevented by the closed valve 35, the plunger will be 30 unimpeded by escaping gas.

The plunger, in its fall, will engage the finger 25 upon the valve and move it downwardly. This will rotate the valve into the position shown in Fig. 4 and the entrance of further gas to the tube 35 therethrough will be prevented.

It will be noted that the spring 28 will hold the finger 25 upon the valve sleeve pointing inwardly, but, due to the lost motion provided by the engagement of the set screw 26 in the slot 29, the 40 valve will be allowed to remain in the position into which it was turned until a partial rotation in the opposite direction is imparted thereto by the plunger. Thus the upward movement of the plunger will open the valve and a downward 45 movement of the plunger past said finger 25 will close the valve.

The charge of liquid in the tank 31 will drain out at the rate desired under control of the choke 33 which will be set to release the liquid and then 50 some of the gas by the time the plunger has fallen to the desired depth. As the gas pressure is thus decreased by the escape of gas from the well, the valve 35 will be forced open and the remaining gas will discharge quickly through the 55 pipe 34.

As the escape of gas into the tube from the casing is closed by valve 22, the pressure of the gas will quickly build up in the casing and depress the liquid level so as to again permit the gas to 60 enter below the plunger as before and a new cycle of operations will be initiated.

The use of the automatically operated valve 22 will save gas which would be otherwise wasted because the pressure of the gas need not be so 65 great throughout the cycle where it does not need to keep the liquid depressed to the lower end of the tube throughout the upward lifting of the load. When the valve 22 is closed on the downward stroke, the pressure of gas is not allowed to 70 exhaust from the casing, but only the gas in the tube may escape.

Further, the entrance of liquid below the plunger for the next load is permitted while the plunger is being lifted. The gas in the casing 75 follows the plunger through the valve 22 and will

not interfere with the entrance of the liquid into the well. Hence, when the plunger reaches bottom, it will be ready almost at once to start upon its next upward stroke. We thus accomplish a faster operation of the device and also save in 5 the amount of gas necessary for operation.

What is claimed is:

1. A plunger lift device including an eduction tube having fluid openings at its lower end, a fluid outlet adjacent its upper end, and a plunger 10 movable from end to end of said tube, in combination with a gaseous fluid inlet in said tube at a level spaced upwardly from its lower end, a valve in said inlet arranged to be opened by upward movement of said plunger past the same and to 15 be closed by downward movement of said plunger past the same.

2. A plunger lift device including an eduction tube having fluid openings at its lower end, a fluid outlet adjacent its upper end, and a plunger 20 movable from end to end of said tube, in combination with a gaseous fluid inlet in said tube at a level spaced upwardly from its lower end, a valve in said inlet, a finger on said valve projecting into the path of said plunger whereby said 25 valve may be operated by said plunger to open and close.

3. A plunger lift device including an eduction tube having fluid openings at its lower end, a fluid outlet adjacent its upper end, and a plunger movable from end to end of said tube, in combination with a gaseous fluid inlet in said tube at a level spaced upwardly from its lower end, a valve in said inlet, means on said valve to be engaged by said plunger on its upward and downward 30 movement in said tube to open and close said valve, and means in said outlet to control the release of gaseous fluid from within said tube and past said valve from the outside thereof.

4. A plunger lift device including an eduction 40 tube having fluid openings at its lower end, a fluid outlet adjacent its upper end, and a plunger movable from end to end of said tube, in combination with a gaseous fluid inlet in said tube at a level spaced upwardly from its lower end, a valve in said 45 inlet, a finger on said valve, and means to hold said finger normally extending inwardly into the path of said plunger to be engaged by said plunger, whereby said plunger may open and close said valve.

5. A plunger lift device including an eduction tube having fluid openings at its lower end, a fluid outlet adjacent its upper end, and a plunger movable from end to end of said tube, in combination with a gaseous fluid inlet in said tube at a level spaced upwardly from its lower end, a valve in said 55 inlet, means on said valve cooperating with said plunger to control the position of said valve, and means to control the time of release of gaseous pressure fluid from said tube after 60 each upward stroke of said plunger so that said plunger in dropping may close said valve before said pressure is released.

6. In a plunger lift device an eduction tube, a plunger movable by gaseous fluid pressure from 65 end to end of said tube, a fluid inlet at the lower end of said tube, a fluid outlet at the upper end thereof, an opening in said tube at a level above the lower end, and a valve in said opening adapted to be opened and closed in response to the upward and downward movements respectively of said plunger in said tube.

7. In a plunger lift device an eduction tube, a plunger movable by gaseous fluid pressure from end to end of said tube, a fluid inlet at the lower 75

- end of said tube, a fluid outlet at the upper end thereof, an opening in said tube at a level above the lower end, a valve in said opening automatically operated by contact of said plunger therewith, and a control device in said outlet to delay the escape of pressure fluid from said tube after each upward stroke of said plunger until said plunger has completed the greater part of its return stroke and close said valve.
8. In a plunger lift device an eduction tube, a plunger movable by gaseous fluid pressure from end to end of said tube, a fluid inlet at the lower end of said tube, a fluid outlet at the upper end thereof, an opening in said tube at a level above the lower end, a valve in said opening automatically controlled by contact with said plunger to open and allow entrance of pressure fluid behind said plunger on its upward stroke and to close off further entrance of pressure fluid when said plunger passes said valve on its downward stroke.
9. In a plunger lift device, an eduction tube having fluid inlets at its lower end, a plunger movable by fluid pressure from end to end of said tube, a valve housing in said tube spaced at a predetermined level above said lower end, a valve in said housing adapted to control passage of fluid to said tube, a finger on said valve, means to hold said finger in a position projecting into the path of said plunger, the contact of said plunger with said finger acting to rotate said valve into open or closed position.
10. In a plunger lift device, an eduction tube having fluid inlets at its lower end, a plunger movable by fluid pressure from end to end of said tube, a valve housing in said tube spaced at a predetermined level above said lower end, a valve in said housing adapted to control passage of fluid to said tube, including a rotatable valve body, a finger secured rotatably to said body, means to limit the relative rotation of said finger on said body, inlets controlled by the rotation of said body, said valve being moved in response to the engagement of said plunger with said finger.
11. In a plunger lift device for a deep well including an eduction tube and a plunger movable freely in said tube from end to end thereof, the method including depressing the liquid level in said well to permit entrance of gaseous fluid below said plunger and thus to move said plunger upwardly, then introducing pressure fluid to said tube at a level above the lower end of said tube and again submerging said lower end in liquid, discharging liquid above said plunger, regulating the rate of discharge of said liquid to prevent discharge of pressure fluid until said plunger has fallen a predetermined distance, and then closing off the entrance of pressure fluid to said tube above its lower end.
